UNITED STATES PATENT OFFICE.

CHARLES H. ALLEN, OF AYCOCK, FLORIDA.

STANDARD FOR LOGGING-CARS.

No. 851,476.

Specification of Letters Patent.

Patented April 23, 1907.

Application filed January 7, 1907. Serial No. 351,223.

To all whom it may concern:

Be it known that I, CHARLES H. ALLEN, a citizen of the United States, residing at Aycock, in the county of Jackson and State of Florida, have invented a new and useful Improvement in Standards for Logging-Cars, of which the following is a specification.

My invention is designed to provide a new and improved standard for logging cars, which is to be arranged on the ends of the transverse bolsters of the car to prevent the logs from rolling off when in transit, but which is capable of adjustment to permit the easy loading or unloading of the log.

Although intended primarily for logging purposes, the device is equally applicable to cars for handling heavy lumber, iron beams, &c.

It consists in the novel construction and arrangement of the adjustable standard, which I will now proceed to describe with reference to the drawings, in which

Figure 1 is a side elevation partly broken away of a transverse bolster of the car equipped with my improved standard. Fig. 2 is a plan view of the same and Fig. 3 is a section on line 3-3 of Fig. 2.

In the drawing, A represents the transverse bolster of the car which has a vertical slot a in the middle of its ends extending entirely through the bolster. In the upper part of this slot there is fulcrumed on a stout horizontal bolt C the adjustable standard B, which plays in the slot and is adjustable from an erect position, as shown in Figs. 1 and 3 in full lines, to the depressed position shown in dotted lines. This standard is made of metal and is preferably bent at an obtuse angle, like a knee, and when in erect position leans outwardly at the top. The lower portion b of the standard which works in the slot is provided with locking and stop devices as follows.

On the bottom side of the end portions of the bolster there is arranged transversely to the bolster a rocking crank shaft E contained in bearings formed by the eyes l l of two eye bolts L L. These eye bolts extend in inclined position from the beveled end face a' of the bolster down through holes bored in the same, so that their eyes are on a level with the lower surface of the bolster.

The rock-shaft E has a middle cranked portion e which when the rock-shaft is in the position shown in full lines strikes against

the lower end b of the standard and holds it in its erect position as seen in Fig. 3. When, however, this rock-shaft is turned to remove its cranked portion e from the range of the lower end b of the standard, as in dotted lines in Fig. 1, then the standard is free to turn on its fulcrum bolt B to the depressed position for the loading or unloading of logs over the end of the same. To limit the downward movement of the standard a cross bolt D extends horizontally through the sides of the bolster and forms a stop in the slot for the lower end b of the standard to strike against.

To operate the rock-shaft E there is rigidly attached to its end an upwardly projecting crank arm F which is loosely attached to a pull bar G extending horizontally any desired distance along the side of the bolster parallel to the same. This pull bar passes through two staples H and I which are wide enough to allow some up and down movement of the pull bar, as shown by dotted lines, in Fig. 1. In the lower edge of the pull bar there is formed a notch g which drops over the lower leg of staple I when the standard B is in its erect position and the locking engagement of this notch over the leg of the staple is maintained by a cam J eccentrically pivoted to the other leg of the staple. When the cam is in its lowest position it locks the pull bar down so that its notch cannot become disengaged from the leg of the staple, but when the cam is turned round and raised, as in dotted lines, the pull bar G may be lifted to disengage its notch g from the leg of the staple and the pull bar G may then be manipulated by its handle K to give it the necessary longitudinal movement to turn the rock-shaft to lock or unlock the standard. To facilitate the turning of the cam J it is formed with a small handle pin j.

I claim

1. A logging standard fulcrumed on a horizontal axis and combined with the bolster, a horizontal rock-shaft arranged transversely to the bolster and having a locking projection adapted to engage the standard and means for turning the rock-shaft.

2. A logging standard fulcrumed on a horizontal axis and combined with the bolster, a horizontal rock-shaft arranged transversely to the bolster and having a locking projection adapted to engage the standard, a rigid crank at the end of the rock-shaft and a pull

rod connected to said crank and arranged in guides in parallel position to the bolster and provided with locking devices.

3. The combination with a bolster slotted vertically at its end, a standard fulcrumed on a horizontal axis and having its end below its fulcrum extended down into the slot of the bolster, a rock-shaft at the bottom of the bolster arranged transversely thereto and having a locking portion adapted to engage the lower end of the standard and means for operating the rock-shaft.

4. The bolster slotted vertically at its end and having a beveled face at the upper part of its end, two eye-bolts extending from said bevel face obliquely to the bottom of the bolster, a transverse rock-shaft journaled on the eyes of said bolts transversely to the bolster and having a locking projection in the middle, and a standard fulcrumed on a horizontal axis in the slotted bolster and having its lower end extended to locking engagement with the rock-shaft.

5. The bolster slotted vertically at its end,

a standard bent at an obtuse angle near the middle and fulcrumed at the bend near the top of the bolster on a horizontal axis within the slot, means for locking the standard in erect position and a stop arranged in the upper part of the slot of the bolster to be engaged by the lower bent extension of the standard to hold the latter in its depressed position.

6. A logging standard fulcrumed on a horizontal axis and combined with a bolster, a horizontal rock-shaft arranged transversely to the bolster and having a locking projection adapted to engage the standard, a crank at the end of the rock-shaft, a pull bar attached to the crank and having a locking notch, a staple enclosing the pull bar and a locking cam arranged on one of the legs of the staple to hold the notch of the pull bar to engagement with the leg of the staple.

CHARLES H. ALLEN.
